UNITED STATES PATENT OFFICE

2,443,538

NECKTIE AND COLLAR ATTACHMENT

William Kopp, Chicago, Ill., assignor to
Walter E. Geweke, Chicago, Ill.

Application February 27, 1946, Serial No. 650,451

7 Claims. (Cl. 2—132)

1

This invention relates to certain novel improvements in a combination collar attachment and tie support, and has for its principal object the provision of an improved construction of this character which will be highly efficient in use and economical in manufacture.

It is an object of this invention to provide an improved device for keeping the wings of a soft fold collar in a neat and attractive condition and to prevent wrinkling and creasing thereof when in use.

The invention embodies the use of a single piece of wire and the loop or loops which form the middle portion thereof for retaining the tie properly positioned between the wings of the collar, and also for holding the knot of the tie firmly in uppermost position.

It is another object of the invention to provide a combined stiffening device for the wings of a soft collar and tie support constructed of a single piece of spring wire bent into the form of an arcuate supporting member adapted to expand and resiliently engage said wings and firmly hold the knot of said tie in desired position.

It is still another object of the invention to provide a combined collar attachment and tie support for the wings of the collar whereby said wings will not creep thereupon due to novel type looped end portions, each loop having a horizontal section a short distance above the points thereof to prevent creeping, whereby the device will retain the wings in a neat, attractive condition and at the same time have means intermediate its ends to keep the knot of a tie in proper location between said wings.

The invention will be best understood by reference to the accompanying drawing showing the preferred form of construction, and in which:

Figure 1 is a perspective view of a collar, with tie in place, and showing one form of the invention having end portions attached to the collar and its intermediate portion positioned within the knot of the tie;

Figure 2 is a side elevational view of that represented and shown in Figure 1;

Figure 3 is a front elevation of the form of invention shown in Figures 1 and 2;

Figure 4 is an enlarged perspective detail view of the preferred form of construction of the piercing points which engage the wings of the collar; and

Figure 5 is a detail side view of the loop and piercing point as shown in Figure 4.

In the drawing, a collar of the turndown style is indicated at 10 and includes the neck band

2

with end portions 11 and 12 detachably joined by a collar button or the like, and this collar being provided with the conventional wings 14 and 15. A conventional type of tie 16 is shown between the wings 14 and 15, the tie embodying a knot 17.

A preferred form of the necktie and collar attachment as shown in the drawings, is therein generally indicated at 20, and comprises necktie engaging means 21 and resilient collar engaging arms 22 and 23 with piercing points 24 and 25. Likewise formed in each of the arms, adjacent the piercing points, are penetration-limiting means in the form of open loops 26 and 27 with offset portions bent laterally substantially at right angles to the flexible and resilient arm portions 22 and 23 and then bent backwards on itself to provide substantial U-shaped loops 28 and 29, said loops 28 and 29 each also providing a rest or place upon which a finger may be placed to force the piercing joints 24 and 25 to penetrate into the wings 14 and 15 on the inner side of said collar 10 when the collar attachment is in applied or wearing position, as shown in Figures 1 and 2. Said loops 28 and 29 further preventing the fabric of the wings 14 and 15 while in use from creeping or crawling up the points 24 and 25 and around the loop 26 and 27 with consequent wrinkling of the collar wings.

Referring to the drawing, it will be seen that the invention is preferably constructed of a single piece of tinned spring wire so as not to rust or corrode and is bent into the desired shape and consists of two arcuate shape arms 22 and 23, with a central connecting portion formed to provide a tie knot engaging means or loop 21. The loop 21 includes an outer inverted U-shaped loop portion, the ends of the leg portions 31 and 32 thereof extended inwardly as at 33 and 34 and terminate in upwardly turned legs 35 and 36 which

terminate by the junction with the top portion of the arcuate arms 22 and 23. At each end of the one piece spring wire a loop is formed, the lower ends 38 and 39 of the arms 22 and 23 extend inwardly and substantially at right angles thereto as indicated at 40 and 41 and then terminate in upwardly turned legs 42 and 43 forming U-shaped loops. The legs 42 and 43 terminating at the upper ends by junction with lateral or backwardly extending U-shaped loops 28 and 29 which terminate with junction of downwardly extending piercing point members 24 and 25 which lie in a plane in front of the U-shaped members formed by loops 26 and 27.

In using the tie and collar attachment the loop 21 is inserted within the knob 17 by forcing it

upwardly at the rear of the knot and beneath the outer layer or wrapping of tie material forming the knot 17 as illustrated in Figures 1 and 2. Points 24 and 25 are inserted in the underside of the collar tips preferably at the ends thereof to hold the collar tips in place; this is done by placing a finger or fingers upon the lateral loops 28 and 29 causing said points to pierce the material when downward pressure is applied thereto. Upon release of the supporting arms 22 and 23 they will expand, holding the piercing points firmly in the collar tips and at the same time causing an upward force upon the wire loop 21 which forces the knot of the tie upwardly, which hold said knot in the desired wearing position.

From the foregoing it is thought that the operation and advantages of the invention will be readily understood and that the invention is also susceptible to various modifications and changes within the scope of the claims hereto appended.

Having thus described the invention, what is claimed is:

1. An attachment for a tie and a collar having wings, comprising a central portion with an upwardly extending loop portion with the lower end member thereof bent away therefrom and then upwardly parallel to said loop to form a clip member, said loop arranged for entering the interior of the knot of a tie, said loop exerting upward pressure to said knot to support the same, said central portion also including arcuate shaped arms extending outwardly therefrom, and piercing points at the ends thereof for engagement with said wings.

2. An attachment for a tie and a collar having wings, comprising a central portion with an upwardly extending inverted U-shaped loop portion with the lower end members thereof bent away therefrom and then upwardly parallel to said loop to form a clip member, said loop arranged to enter the interior of the knot of a tie, said loop exerting upward pressure to said knot, said loop also including arcuate shaped resilient arms extending outwardly therefrom, and piercing points at the ends thereof for engagement with said wings, looped portions on said arms adjacent the piercing points including a U-shaped loop arranged substantially at right angles therewith for use in adjusting the attachment to said wings.

3. An attachment for ties, and collars having wings, comprising a single length of wire, the intermediate portion of which is bent to form an inverted U-shaped loop portion with the lower end members thereof bent away therefrom and then upwardly parallel to said loop to form a clip member, the upper ends of said vertical members being bent outwardly to form two arcuate shaped resilient arms with piercing points at the terminals thereof, said inverted U-shaped loop portion to be inserted into the knot of said tie, and said points to be inserted in the wings of said collar.

4. An attachment for ties, and collars having wings, comprising a single length of wire, the intermediate portion of which is bent to form an inverted U-shaped loop portion with the lower end members thereof bent backwardly and then upwardly parallel to said loop portion forming a clip with a loop and vertical members, the upper ends of said vertical members being bent outwardly to form two arcuate shaped resilient arms with piercing points at the terminals thereof, said inverted U-shaped loop portion to be

inserted into the knot of said tie to be enclosed by said knot, said loop exerting upward pressure to the interior of said knot to support the same, said points to be inserted in the wings of said collar, looped portions on said arms adjacent the piercing points including a U-shaped loop arranged substantially at right angles to said arms for use in adjusting the piercing points into said wings.

5. In devices for holding the wings of a turn-down collar in place and also supporting the knot of a tie between said wings, a member including arms and piercing points on said arms for engagement with said wings, said member including a central portion with a pair of downwardly extending arms terminating to form an upwardly projecting loop, said loop for entering the interior of said knot to exert upward pressure thereto to support the same, and means on said arms for preventing the fabric of said wings from "creeping" or "crawling" up said piercing points onto said arms when said points are engaged with said wings, said means comprising a loop arranged substantially at right angles to said arms.

6. An attachment for collars having wings and ties, comprising a single length of wire and a member with a central loop which is bent to form an inverted U-shaped loop portion with the lower end members thereof bent away therefrom and then upwardly parallel to said loop to form a clip member, said loop portion adapted to extend within the knot of said tie, said member including arms and piercing elements on said arms for engagement with said wings, looped portions on said arms adjacent the piercing elements, and means associated with said looped portions for preventing the fabric of the wings from working up past said elements and loop when said elements are engaged with the wings.

7. A necktie support formed of a continuous strand of spring wire and comprising a member having its intermediate part formed into a vertically arranged loop which is bent to form an inverted U-shaped loop portion with the lower end members thereof bent away therefrom and then upwardly parallel to said loop to form a clip, said loop portion adapted to exert upward pressure and also adapted to extend into the interior knot of the necktie, said strand also comprising arcuate shaped arms terminating adjacent the points of the collar and extending from the loop and pointed for penetrating the collar material, and means adjacent said pointed ends for preventing the fabric of the wings from working up past said points onto said arms.
